UNITED STATES PATENT OFFICE

2,127,428

RAILWAY BRAKE MECHANISM

Theodore H. Schoepf and David M. Ritchie, Cincinnati, Ohio, assignors to The Cincinnati Traction Building Company, Cincinnati, Ohio, a corporation of Ohio

Application February 24, 1937, Serial No. 127,350

21 Claims. (Cl. 192—3)

Our invention relates to the control of the supply of steam to a steam engine, or supply of fuel oil or gas to an internal combustion engine carried by a railway vehicle and utilized for propelling the said vehicle through mechanical means or electrical means, and wherein the vehicle is equipped also with usual or customary fluid pressure brakes.

The essential object of this invention is to devise electrically operative mechanism whereby the steam or fuel supply is automatically shut off from the engine responsive to manipulation of a control valve utilized to apply the fluid pressure brakes of the vehicle.

It is a further object of this invention to provide means comprehended in said mechanism, whereby the functioning thereof will take place or become effective only when the magnetic track brakes of the vehicle are applied.

It is a further object of this invention to provide, in such mechanism, means whereby the fuel supply valve may be manually operated irrespective of the application of the track brakes.

It is a further object of this invention to provide such means which is adjustable and which may be made effective for any and all applications, either service or emergency of the fluid pressure brakes and/or track brakes as may be desired.

It is a further object of this invention to provide electric motor means for opening and closing the fuel or steam valve of a railway vehicle automatically responsive to the application of the fluid brakes of the vehicle and/or responsive to the application and energization of the track brakes of the vehicle.

It is a further object of this invention to provide, in such valve operating means, an electric motor which is reversible and means responsive to the escape of fluid from the air brake train line to reverse the direction of rotation of the motor.

It is a further object of this invention to provide, in such mechanism, means responsive to movement and position of the fuel or steam valve for determining the subsequent direction of rotation of the motor.

It is a further object of this invention to provide, in such mechanism, manually operable means for operating the valve independently of the means responsive to the application of the vehicle brakes.

It is a further object of this invention to provide, in such mechanism, quick action reversing switch means responsive to the position and

direction of movement of the valve to determine the direction of subsequent rotation of the motor.

It is a further object of this invention to provide, for operation of the fuel or steam valve of a railway vehicle, means responsive to the reduction of fluid in the air brake train line of the vehicle for causing movement of the valve stem in one direction and means responsive to restoration of pressure in the air brake train line to cause reverse movement of the valve.

These and other objects and advantages will appear from the following description taken in connection with the drawings.

This application is a continuation in part of our copending application Serial No. 89,650, filed July 8, 1936.

In the drawings:

Figure 1 is a diagrammatic view of mechanism illustrative of this invention, the parts being shown in the position of normal operation, with the fuel or steam valve open and the illustrated track brakes free of the rail, various of the component mechanisms being shown in section;

Figure 2 is a front elevational view of a preferred form of valve actuated reversing switch for use in the practice of this invention;

Figure 3 is a section taken on the line 3—3 of Figure 2;

Figure 4 is a view, partly in section, of a modified form of electrical valve actuating mechanism;

Figure 5 is an elevational view, partly in section, of a modification of the pneumatic reversing switch mechanism illustrated in Figure 1;

Figure 6 is a diagrammatic view illustrating the application of the principles of this invention to a modified form of electromagnetic track brake;

Figure 7 is a diagrammatic view illustrating the application of the principles of this invention to a second form of electromagnetic track brake which is positioned, for application, by means of a lever actuated in opposition to a tension spring by a solenoid connected within the brake energizing circuit; and

Figure 8 is a diagrammatic view illustrating the use, in the practice of this invention of a preferred form of combined relay valve and valve opening circuit interrupter switch.

Referring to the drawings in detail and with reference particularly to Figure 1, the conventional air brake train line, designated 1, is provided at each end with cut-out cocks 2 and coupling hoses 3. The air brake train line 1 is connected by the pipe 4 with the conventional brake

valve 5 having the inlet pipe 6 thereof connected to a suitable supply of pressure and the exhaust pipe 7 thereof connected to suitable exhaust means. The conductor's valve 9 is connected to the air brake train line 1 by means of the conductor's valve pipe 8. Also connected to the air brake train line 1, by means of the pipe 10, is the track trip valve 11 which is adapted to cooperate with suitable track trip means 12 to release the pressure from the air brake train line 1.

The air brake train line 1 is also connected, by means not shown, in a conventional manner to the fluid operating means for the wheel brakes of the track vehicle upon which the air brake train line 1 is supported. Pressure in the air brake train line 1 may be reduced by the actuation of brake valve 5, track trip 11 or the conductor's valve 9 or, by the occurrence of breaks in the train line 1, the coupling hoses 3, or by accidental separation of either of the coupling hoses 3 from other coupling hoses to which they may be attached.

Also connected to the air brake train line 1 by means of pipe 13 is the relay valve 14 which is provided with an internal slide 15 which is urged in one direction by pressure from the air brake train line and in the opposite direction by means of the spring 16. The slide 15 of the valve 14 is provided with a port 17. The pressure tank 18 is connected by means of the pressure tank pipe 19 to the body of the valve 14. The track brake positioning means comprises the fluid engine 20 having the top of the cylinder 21 thereof connected by means of pipe 22 to the body of the relay valve 14, the pipe 22 being disposed in alignment with and below the pipe 19.

The relay valve exhaust pipe 23 is also connected to the valve body 14 below and in alignment with the pipes 19 and 22. The spacing and connection of the pipes 19, 22 and 23 with the body of the relay valve 14 is preferably such that, when the valve slide 15 is held in the lowermost position by pressure from the air brake train line 1, the end of the pipe 19 is blocked by the slide 15, while the ends of the pipes 22 and 23 communicate through the port 17 of the slide 15 to permit exhaust of fluid from the cylinder 21 of the fluid engine 20 through pipe 22, port 17 and relay valve exhaust pipe 23.

Furthermore, due to the disposition of the respective pipes, when the slide 15, upon reduction of the pressure in the air brake train line 1, is moved upwardly by the spring 16, the end of the relay valve exhaust pipe 23 is first closed by the slide 15 before the ends of the pipe 19 and pipe 22 are connected by the port 17 of the slide 15. Therefore, upon reduction of fluid pressure in the air brake train line 1, the relay valve slide 15 will move upwardly from the position illustrated in Figure 1 to close the end of the relay valve exhaust pipe 23 and connect the ends of pipes 19 and 22, whereby fluid pressure from the pressure tank 18 will be transmitted through pipe 19, port 17, and pipe 22 to the top side of the cylinder 21 of the fluid engine. The fluid engine 20 is provided with a piston 24 slidable within the cylinder 21 and having a rigidly connected piston rod 25 which is connected at its opposite end to the top of the track brake, hereinafter more clearly described.

The piston 24 is urged upwardly by the spring 26 which is disposed about the piston rod 25 and between the lower side of the piston 24 and the lower wall of the cylinder 21. When fluid pres-

sure is introduced into the cylinder 21 of the fluid engine 20, the piston 24 and the piston rod 25 are moved downwardly against pressure of the spring 26 to place the attached track brake 27 in predetermined position adjacent the rail 28, whereby, upon energization of the coil of the track brake 27, the track brake 27 will be urged, by this energization, against the rail 28 because of the disposition of the rail 28 within the magnetic field of the energized track brake 27.

In Figure 6, is illustrated a form of track brake which is normally suspended by means of springs 178 so closely adjacent the rail that the track brake requires no preliminary positioning before its energization. In other words, immediately upon energization of the coil 72 of the track brake shoe 27 illustrated in Figure 6, the brake shoe 27 is brought into braking engagement with the rail. When the above described structure and the hereinafter described structure are utilized with brakes of the type illustrated in Figure 6, the pipe connection 13 will be omitted from the air brake train line 1, the pressure tank 18, the relay valve 14, the brake positioning fluid engine 20 and associated parts being also omitted as shown in Figure 6.

The structure of this invention may also be applied to another type of track brake as diagrammatically illustrated in Figure 7, wherein the brake shoe 27 is normally resiliently suspended by tension springs 178, as in Figure 6, the spacing of the brake shoe 27 of Figure 7 above the rail is substantially greater than that of the spacing of the brake shoe of Figure 6 and, therefore, it is necessary, for application of the brake to the rail, that the shoe be first positioned somewhat in the same manner as is the shoe 27 of Figure 1 positioned. For this purpose, a positioning lever 180 is provided which is pivoted at 180a and normally urged upwardly by means of a tension spring 181 in the same manner as is the shoe 27 supported by the springs 178 and which is, immediately upon energization of the coil 72 of the brake shoe 27, drawn downwardly by means of a solenoid 179 connected within the brake coil energizing circuit and having associated therewith an armature connected to the lever 180. Thus, upon energization of the coil 72 of the brake shoe 27 illustrated in Figure 7, the solenoid 179 draws the brake shoe positioning lever 180 downwardly against tension of the lever supporting spring 181 to place the shoe 27 sufficiently close to the rail 28 to bring the rail within the magnetic field of the shoe. The shoe 27 is thus applied to the rail 28 by energization of the coil 72 thereof.

In the application of the principles of our invention to such brake mechanism as is illustrated in Figure 7, the pipe connection 13, the relay valve 14, the fluid track brake positioning engine 20 and associated parts will be omitted, as is the case when the principles of our invention are applied to brakes of the type illustrated in Figure 6.

The details of a form of the brake diagrammatically illustrated in Figure 6 are disclosed in the United States Letters Patent No. 725,985 granted April 21, 1903, to F. C. Newell, while the details of a form of the brake illustrated diagrammatically in Figure 7 are disclosed in the United States Letters Patent No. 1,724,266 granted August 13, 1929, to T. Elliott.

Also connected to the air brake train line 1, by means of pipe 29, is the valve opening circuit in-

5   interrupter switch mechanism comprising the fluid engine 30 having contained in the cylinder thereof of the piston 31 which is connected by means of the piston rod 32 with the switch plate 33. The compression spring 34 which is disposed between the upper wall of the cylinder and the upper surface of the piston 31 constantly urges the switch plate 33 downwardly out of engagement with the cooperating contacts, but during normal conditions, when pressure produced in the cylinder of the fluid engine 30 by its connection with the air brake train line 1 is sufficient to overcome the force of the spring 34, the switch plate 33 is retained in engagement with the cooperating switch contacts as illustrated in Figure 1. However, immediately upon reduction of pressure in the air brake train line to such an extent that pressure in the fluid engine 30 is reduced sufficiently to allow the spring 34 to act, the switch plate 33 15   is removed from engagement with its cooperating contacts.

20

The branch pipe 35 which also leads from the air brake train line 1 is connected by the pipe 36 to the one-way valve 31 and also by means of pipe 38 with the check means 39 which, in turn, is connected by means of pipe 40 with the pipe 41 leading from the one-way valve 37, and with the pipe 42 which is also connected to the cylinder of the fluid engine 43 which operates the primary circuit switch. The fluid engine 43 is similar to the fluid engine 30, being provided with the piston 44, the spring 45 and piston rod 46. The piston rod 46 has rigidly secured thereto the annular switch plate support 47 which is adapted to support the switch plate 48 which is constantly urged thereagainst by means of the spring 49 having one end in engagement therewith and the other end in engagement with the support member 50 which, like the member 41, is also rigidly secured to the piston rod 46.

40 rigidly secured to the plate 48. As in the operation of the interrupter switch, when fluid pressure in the cylinder of the fluid engine 43 is reduced below a predetermined amount, the spring 45 will move the piston rod 46 downwardly at a rate of speed depending upon 4.5 the escape of fluid from the cylinder of the fluid engine 43 to bring the switch plate 48 into engagement with the cooperating contacts of the primary circuit.

50 After the initial engagement of the switch plate 48 with its cooperating contacts, the piston rod 46 will continue to move downwardly, compressing the spring 49. Upon restoration of fluid pressure in the cylinder of the fluid engine 43, 55 the switch plate 48 will remain in engagement with the cooperating contacts of the primary circuit during the time required for the upward movement of the piston rod 46 to permit the spring 49 to return to its extended position, as 60 illustrated in Figure 1. The pipes 41 and 42 are connected by means of the pipe 51 with the check means 52 which, in turn, is connected by means of the pipe 53 with the cylinder of the fluid engine 54 which actuates the fluid operated reversing switch. 65

The construction and operation of the fluid engine 54 is similar to that of the fluid engine 43, there being provided the piston 55 in the cylinder of the fluid engine 54 which is urged downwardly by the spring 56 and upwardly by fluid pressure, and which piston 55 is rigidly connected to the piston rod 57 which carries a plurality (four) of switch plates 58, 59, 60 and 61 which are supported thereon in the same manner in which the switch plate 48 is supported

on the piston rod 46, save that the upper switch plates 58 and 59 are urged upwardly with respect to the piston rod 57, while the lower switch plates 60 and 61 are urged downwardly with respect to the piston 57 by the respective cooperating compression springs which are similar and which are all designated 62.

As shown in Figure 1, when the pressure in the cylinder of the fluid engine 54 is sufficient to overcome the spring 56, the piston 55 moves upwardly at a rate depending upon the flow of fluid into the cylinder of the fluid engine 54. The rate of flow into the cylinder of the fluid engine 54 through the pipe 53 is controlled by the check means 52. The upward movement of the piston 55 places the switch plates 58 and 59 in engagement with their cooperating switch contacts, while downward movement of the piston 57, when continued sufficiently to remove the switch plates 58 and 59 from engagement with their cooperating switch contacts, places the switch plates 60 and 61 in engagement with their cooperating switch contacts.

The one-way valve 37 prevents the flow of fluid from the branch pipe 35 through pipe 36 directly to pipe 41, while permitting the flow of fluid from the pipes 42 and 51 through the pipe 41 to the pipe 36. Therefore, fluid flowing from the air brake train line 1, through branch pipe 35, is required to pass through the pipe 38, check means 39 and pipe 40 before reaching the pipe 42 and further through pipe 51 and check means 52 before reaching the pipe 53 and the cylinder of fluid engine 54. The construction of the check means 39 and 52 is similar, each of these members being provided with replaceable circular rubber disks having a central aperture of predetermined size, which rubber disks are clamped between two annular flanged metallic members connected by bolts. 40

In order to change the rate of flow through the respective check means, it is merely necessary that a rubber disk having an aperture of desired size be inserted therein. The rubber disk in the check means 39 is preferably provided with a larger orifice than that of the disk in the check means 52. Therefore, when, after reduction of pressure in the air brake train line 4, the pressure therein is restored, fluid will pass through the check means 39 at a higher rate than through the check means 52. Therefore, the fluid engine 43 will be more quickly actuated than will the fluid engine 54. Likewise, upon reduction of pressure in the air brake train line 4, fluid passing from the cylinder of the fluid engine 43 will be permitted to pass freely through the one-way valve 37 as well as through the check means 39. However, all fluid passing from the cylinder of the fluid engine 54 must pass through the check means 52 before reaching the pipe 51 and the path of fluid from the fluid engine 43.

In Figures 1 and 4, 63 designates the fuel or steam line of the vehicle propelling unit which it is desired to close upon energization and application of the track brake 27. In Figures 1 and 4, the means for closing or blocking this line 63 comprises a gate valve. In Figure 1, the gate valve is designated 64 and the stem 65 thereof is provided with a rack 66 having a projection 67 at the end thereof. The rack 66 is adapted for constant engagement with the pinion 68 which is rigidly secured to one end of the rotor shaft 69 of the electric motor 70, which rotor shaft 69 has the hand wheel 71 rigidly secured to the opposite end thereof. By means of the hand 75

wheel 71, when the motor 70 is de-energized, the valve 64 may be opened, closed, or adjusted manually in such manner as may be desired.

The motor 70 is of the direct current type and the coil of the brake 27, which is designated 72, is also adapted for direct current energization.

The negative terminal of the brake coil 72 is connected to the wire 73 which is the negative wire. The positive terminal of the brake coil 72 is connected to the positive wire 74 of the brake energizing circuit. The wire 73 is connected by means of the branch wire 75 to the primary circuit wire 76.

The wire 74 is connected to the primary circuit branch wire 77, which is connected to primary circuit switch contact 78. The other contact of the primary circuit switch is designated 79 and is connected by means of wire 80 with the contact 81 of the manual switch 83. The primary circuit wire 76 is connected to the contact

82 of the manual switch 83. The manual switch 83 is a double-bladed knife switch, having one terminal 84 thereof connected to the positive side of a suitable source of power 85 which may be a storage battery or any other suitable source of direct current.

The opposite terminal 86 of the manual switch 83 is connected to the negative side of the source of power 85. Whenever the manual switch 83 is closed, the contacts 81 and 84 are connected by one blade of the switch and the contacts 82 and 86 are also connected by the other blade of the switch.

Upon further connection of the contacts 78 and 79 by the switch plate 48 of the primary circuit switch, a circuit is completed for energizing the brake coil 72, which circuit extends as follows:

from the positive side of the source of power 85, from contact 84, through one switch blade to contact 81, through wire 80 to contact 79, through switch plate 48, through branch wire 77 to wire

74, through brake coil 72, back through wire 73, through wire 75 and wire 76 to contact 82, through the other switch blade to contact 86 and thus to the negative side of the source of power 85.

Therefore, whenever the manual switch 83 and the primary circuit switch are closed, the branch wire 77 and the wire 76 are energized, the branch wire 77 being positive and the wire 76 being negative. Also, whenever the wire 76 and the wire 77 are thus energized, the brake coil 72 is also energized.

Whenever the switch 83 is manually opened, the power source 85 is isolated from the operative circuit and energization of the brake coil 72 is effectively prevented. Also, completion of the energizing circuit depends upon

the position of the switch plate 48 of the primary circuit switch which is operated only upon reduction of pressure in the air train line sufficiently to cause the flow of a predetermined amount of fluid from the cylinder of the fluid engine 43.

The positive branch wire 77 of the primary circuit is connected by the wire 87 with the wire 88 which leads to the positive terminal of the winding of the motor 70. The negative wire 76 is connected to the wire 89 which leads to the negative terminal of the winding of the motor 70.

Upon energization of the wires 76 and 77, the wire 88 will be positively energized and the wire 89 will also be negatively energized.

In order to reciprocate the valve stem 65 to the right, it is necessary that the motor 70 rotate in one direction, while, in order to reciprocate the valve stem 65 in the opposite direction to close the valve, it is necessary that the sense of rotation of the motor be reversed. For this

purpose, means is provided for reversing the energization of the brush terminals of the motor 70. In addition to the fluid operated reversing switch having switch plates 58, 59, 60 and 61, this means also includes the valve actuated reversing switch which has the slide member 90 of inverted U-shape which is adapted to be contacted adjacent the end of each reciprocation of the valve stem in either direction by the projection 67 which thus moves the slide member 90 either to the right or to the left in order to swing the switch lever 91 about its pivot 92 in such manner that the contact 93 thereof will be engaged with the contact 94 after the valve has been opened and will be engaged with the contact 95 after the valve has been closed. Electrical connection is provided between the contact 93 of the lever 91 and the wire 96 which is connected to the positively energized wire 87. When the primary circuit switch and the manual switch are closed, the contact 93 will always be positively energized.

The switch contact 94 is connected by means of wire 97 with the contact 98 of the fluid operated reversing switch, and the opposite contact 99 of the fluid operated reversing switch is connected by the wire 100 to one brush terminal of the motor. The opposite brush terminal is connected by wire 101 to the reversing switch contact 103, while the opposite switch contact 102 is connected by means of wire 104 to the wire 75.

In the position of parts illustrated in Figure 30, the motor 70 is inoperative, but, upon the operation of the primary circuit switch to bridge contacts 78 and 79 with the switch plate 48, a circuit is completed from the positive branch wire 77, through wire 87, wire 96 and contacts 93 and 94 through wire 97 to contact 98, through switch plate 58 to contact 99, through wire 100 to one brush terminal of the motor and thence from the other brush terminal through wire 101 to contact 103, through switch plate 59 to contact 102 and through wires 104 and 75 to negative wire 76. Thus, upon the closing of the primary circuit switch, the motor will rotate in such direction that the pinion 68 will cause reciprocation of the rack 66 and the supporting valve stem 65 to the left, as seen in Figure 1. Adjacent the end portion of this reciprocation, the switch lever 91 will be swung clockwise about its pivot 92, whereby to engage the contact 93 thereof with the contact 95.

The wire 104 is connected by the wire 105 with the contact 106 of the fluid operated reversing switch and the opposite contact 107 of the reversing switch is connected by the wire 108 with the wire 100. The valve actuated reversing switch has the contact 95 thereof connected by means of wire 109 with the circuit interrupter switch contact 110, while the opposite interrupter switch contact 111 is connected by means of wire 112 with the contact 113 of the fluid operated reversing switch. The opposite reversing switch contact 114 is connected by means of wire 115 with the wire 101 which leads to the brush terminal of the motor 70. Electrical connection between the contact 95 and the contact 113 depends upon the bridge of the contacts 110 and 111 by the switch plate 33, and this bridging of the contacts 110 and 111 depends upon maintenance of sufficient pressure in the cylinder of the fluid engine 30 to overbalance the spring 34 thereof. Therefore, after the above operation of the motor to close the valve has occurred and the contacts 93 and 95 are engaged, the circuit between the contact 95 and contact 113 will be broken due to the fact that the circuit between

contacts 110 and 111 will not be completed until restoration of predetermined pressure in the air brake train line.

The reduction of pressure in the air brake train line necessary to cause the above-described operation of the motor 70 to close the valve 64 and engage the contacts 93 and 95 will also cause sufficient reduction of pressure in the fluid engine 54 to permit the spring 56 to draw the piston 57 of the fluid operated reversing switch downwardly in such manner as to separate the switch plate 58 from engagement with the contacts 98 and 99, and the switch plate 59 from engagement with the contacts 102 and 103. The switch plate 60 will bridge the contacts 106 and 107 and the switch plate 61 will engage and bridge the contacts 113 and 114. When the fluid operated reversing switch is in this position, a circuit from the negative wire 76 will be completed through a wire 75, wire 104, wire 105, contact 106, switch plate 60, contact 107, wire 108 and wire 100 to the brush terminal which was previously positively energized, but which is now negatively energized. A circuit will be completed from the other brush terminal through wire 101, wire 115 to contact 114, through switch plate 61, contact 113, wire 112, contact 111, switch plate 33, contact 110, wire 109, contact 95, contact 93, wire 96, wire 87 to positively energized branch wire 77 to reverse the previous energization of the brush terminals of the motor 70. As explained above, this circuit will not be completed until sufficient pressure has been restored to the air brake train line 1 to cause a bridging of the contacts 110 and 111 by the switch plate 33.

Operation

With the parts in normal position, as illustrated in Figure 1, reduction of the pressure in the train line caused by the occurrence of rupture thereof or by rupture of the hose connections 3 or separation thereof from other connected hose connections, or by operation of the brake valve 5, the track trip valve 11, or the conductor's valve 9, pressure in the relay valve 14 will be reduced to permit the spring 16 to urge the slide upwardly into such position as to permit the fluid engine 20 to position the brake shoe 27.

Simultaneously, the fluid engine 30 will operate to remove the switch plate 33 from engagement with the contacts 110 and 111 and thus open the valve opening circuit. Fluid will escape from the fluid engines 43 and 54, but, for the reasons pointed out above, the rate of escape from the fluid engine 43 will be substantially greater than that from the fluid engine 54, whereby the switch plate 48 will close the primary circuit by bridging the contacts 78 and 79. Due to the relatively slow downward movement of the piston rod 51, the switch plates 58 and 59 will remain in engagement with their respective contacts and the energization of the motor 70 will, as above described, take place to cause reciprocation of the valve stem 65 to the left to close the valve. The rate of escape of fluid from the cylinder of the fluid engine 54 will be such that the reciprocation of the valve stem 65 will be accomplished by the motor before the switch plates 58 and 59 are removed from engagement with their respective contacts.

Adjacent the end of the leftward traverse or reciprocation of the valve stem 65, the cooperation of the projection 67 thereof with the slide member 98 will place the contact 93 of the switch lever 91 in engagement with the contact 95. The

switch plate 33 will remain disengaged from the contacts 110 and 111 and the coil 72 of the track brake 27 will have become energized as soon as the contacts 78 and 79 are engaged by the switch plate 48. The track brake 27 will then be positioned and applied by energization, the valve will be closed and the primary circuit which energizes the brake 27 will also be closed. The valve opening circuit will be opened because of the separation of the switch plate 33 from the contacts 110 and 111. After the escape of fluid from the cylinder of the fluid engine 54, the valve opening circuit will be otherwise complete.

Immediately upon restoration of pressure in the air brake train line 1, the relay valve slide 15 will block the pipe 19 and vent the fluid engine 20 through the relay valve exhaust pipe 23. Simultaneously, the switch plate 33 will be engaged with the contacts 110 and 111. Due to the restriction provided by the one-way valve 37 and check means 39 and 52, the switch plates 60 and 61 will remain in engagement with their respective contacts and the switch plate 48 will likewise remain in contact with the contacts 78 and 79 for such time as to permit of sufficient energization of the motor 70 in proper direction to cause reciprocation of the valve stem 65 toward the right in order to open the valve.

During the latter portion of this reciprocation, the contact 93 will again be placed in engagement with the contact 94 and subsequently, due to restoration of fluid in the fluid engine 43, the switch plate 48 will be removed from engagement with the contacts 78 and 79 to interrupt the primary circuit and to de-energize the brake coil 72 and subsequent to this, the restoration of fluid pressure in the fluid engine 54 will cause sufficient upward movement of the piston rod 57 to place the parts of the fluid operated reversing switch in the position illustrated in Figure 1.

The rate of passage of fluid in either direction through the check means 39 and 52 may be varied, as described above, by provision of a rubber disk having a suitable aperture for this purpose. Likewise, the adjustment of the switch plate 48 on the piston rod 46, and of the respective switch plates 58, 59, 60 and 61 on the piston rod 51, along with variation of the characteristics and length of the springs 49 and 62, provides means whereby the operating characteristics of the respective switches may be widely varied and/or adjusted.

A preferred form of valve actuated reversing switch is illustrated in Figures 2 and 3, wherein is provided, as shown, a box-like frame 116 having a suitably insulated binding post 117 in the top wall thereof for connection of the wires 87 and 96 and having in one side wall a suitably insulated binding post 118 having the switch contact 94 integral therewith and adapted to have the wire 97 connected thereto. In the opposite side wall is disposed the binding post 119 which is similar to the binding post 118 and which is provided with the integral contact 95 and which is adapted to have the wire 109 connected thereto. The frame 116 is provided with four screw-threaded ears 120 which are adapted to provide means of connection and support for the front cover plate 121 which is secured thereto by means of screws 122. Supported between the opposite side walls at the lower end of the frame 116 is the bifurcated bracket 123 which is secured to the respective side walls by screw bolts 124 and which has concentric bores in the respective

furcations 125 and 126, through which extends the pivot bolt 127.

The lower portion of the switch lever comprises a metal member 128 provided at its lower end with an aperture adapted to receive the pivot bolt 127 provided adjacent its central portion with an arcuate slot 129 and provided at its upper end with a pair of furcations 130, between which is secured, by means of rivets 131 or the like, the member 132 which comprises a bar of suitable insulating material having the double lever arm switch contact member 93 attached to its upper end. The member 93 is provided with a binding post 133, to which is attached the lower end of the wire 96 which has its upper end secured to the binding post 117.

Also pivotally supported upon the pivot bolt 127 is the snap lever 134 having the pin member 135 secured in an aperture in the upper end thereof by drive fit. The forward end of this pin member is cylindrical and extends through and beyond the arcuate slot 129 in the metal member 128. Rearwardly of the snap lever 134, the pin member 135 is provided with an enlarged portion having thereon a step adapted to receive one end of the tension spring 136 which has its opposite end secured in the eye bolt 137 which is secured in the bottom side wall of the frame 116. Disposed forwardly of the members 128 and 134 are apertures 30 in the opposite side walls of the frame 116 through which extend the connector bar 139 which is supported by out-struck ears 138 adjacent the apertures in the side walls of the frame 116. This connector bar is adapted to be suitably connected at its left end with the valve stem 65 in any suitable manner so that reciprocation of the valve stem 65 will cause like reciprocation of the connector bar 139. The connector bar 139 is provided with a slot 140, into which the pin member 135 extends, as shown in Figure 3.

During the above described operation of the electric motor operated valve, the connector bar 139, during its reciprocation, will engage the opposite sides of the pin member 135 with the opposite end surfaces of the slot 140 whereby, adjacent each end of the reciprocatory movement, the pin member 135 will be carried from one end of the arcuate slot 129 to the opposite end thereof, or rather past the dead center therein and, after the pin 135 has passed the central portion of the arcuate slot 129, the tension of the spring 136 will draw it to the opposite end of the arcuate slot 129. Therefore, at a predetermined point, adjacent each end of the reciprocation of the connector bar 139, the switch contact 93 will be quickly swung either from the contact 94 to the contact 95, or from the contact 95 to the contact 94.

In Figure 4, the valve 141 is provided with a cylindrical threaded stem 142 having a centrally screw-threaded gear 143 disposed thereabout and retained in position by the guide means 144 integral with the valve body. The pinion 68 on the rotor shaft 69 of the motor 70 is adapted to mesh with the gear member 143 in order to open and close the valve. The opposite end of the rotor shaft 69 of the motor 70 is provided with the hand wheel 71 and the motor 70 is adapted to be operated and controlled in the same manner as the motor 70 illustrated in Figure 1 and described above.

At its outer end, the valve stem 142 is provided with a projection 145 in the form of a pin which is adapted to receive a complementary aperture in the connector bar 139 which is se-

cured thereon by means of the washer 146 and cotter pin 147. If desired, any other suitable form of projection as, for instance, a projection similar to the projection 67 of the valve stem 65 in Figure 1, may also be provided.

The details of a preferred form of fluid operated reversing switch are illustrated in Figure 5, wherein the panel 148 is provided for supporting the parts thereof. The fluid engine 54, as therein shown, comprises a flanged cylinder casting 149 provided with supporting flanges 150. The cylinder casting is provided with a cylinder 151 below which is disposed a fluid chamber 152. The top of the cylinder is closed by the cylinder cap 153 provided with a central bore or aperture 154 for slidably receiving the piston rod 57. The lower end of the piston rod 57 is provided with a suitable reduced and screw-threaded portion upon which is disposed the piston 55 which is secured thereon by means of washer 155 and nut 156. Disposed about the lower end of the piston rod 57 and between the inner surface of the cylinder cap 153 and the upper surface of piston 55 is the compression spring 56. An adjusting screw 157 is suitably screw-threaded through the lower portion of the casting 149 and provided with a suitable lock nut 158. This adjusting screw is adapted to provide means for limiting the downward movement of the piston 55 in the cylinder 151 in predetermined manner. The flanges 150 of the casting 149 are secured by means of bolts 159 to the panel 148. The upper end of the piston rod 57 is provided with a smooth cylindrical portion adapted to be received in a suitable bearing aperture provided in the bearing bracket 160 which is rigidly secured by means of bolts 161 to the panel 148.

The piston rod 57 is screw-threaded throughout a substantial portion and the respective switch plates comprise cylindrical metal members 162 having rigidly attached and preferably shrunk on conducting sleeves 163 of suitable conducting material. The cylindrical metal members 162 may be adjusted axially of the piston rod 57 by being screwed therealong and may be locked in desired position by means of lock nuts 164 disposed above and below each member 162. Although only the switch plate 61 is shown in section in Figure 5, the construction of members 58, 59 and 60 is identical with this showing.

Disposed at each side of the piston rod 57 and secured to the panel 148 by bolts 165 is a contact support member 166 of L-section having adjacent the inner and outer surfaces thereof a sheet of insulating material 167. Suitable registering apertures are provided, which extend through the sheets 167 and the interposed flange of the contact support member 166 and through each of these apertures extends a bushing 168 of suitable insulating material.

Supported within each of the bushings 168 is a cylindrical contact support member 169 provided with an inwardly disposed flange 170 and a central aperture 171 at its inner end, adapted to receive the reduced end portion of a contact member 172 which has an enlarged head which is received in the bore 173 of the contact support member. The cylindrical hollow portion of the contact support 169 extends outwardly beyond the outer insulating sheet 167, and a lock nut 174 is screw-threaded thereon and separated from the outer end of the bushing 168 and the outer surface of the insulating sheet 167 by means of the insulating washer 175. By this means, the contact support member 169 is fully insulated

from the contact support member 166. Screw-threaded in the outer end of the contact support 169 is a plug member 176 having a reduced screw-threaded portion which is adapted to receive suitable nuts for securing the appropriate wire thereto. Interposed between the head of the contact member 172 and the inner end of the member 176 is a compression spring 177 which is adapted to resiliently urge the contact member 172 inwardly toward the appropriate switch plate. While only one of these contact members, namely, that diagrammatically designated 113 is shown, the construction and support of the other contact members is identical therewith.

As above explained, the respective switch plates or contact members 58, 59 and 60 may be adjusted, as desired, axially with respect to the piston rod 57. Likewise, the position of these members with respect to the contact members may be also adjusted by adjustment of the adjusting screw 151 which limits the downward movement of the piston rod 57. By this means, the operating characteristics of the fluid operated reversing switch illustrated in Figure 5 may be varied, within rather wide limits, as desired. Limitation of the downward movement of the piston 55 in the cylinder 151 by means of the adjusting screw 151 increases the capacity of the fluid chamber 152 and also increases the initial compression of the spring 56. The cooperation of the switch plates or contact connecting members 58, 59, 60 and 61 with their respective contacts is otherwise, during operation, the same as that of the form of fluid operated switch illustrated in Figure 1 and described above.

In Figure 8 we have illustrated a preferred form of valve opening circuit interrupter switch which is a part of, and which is operated by, the relay valve 14. In this construction, the piston rod 32, which supports the switch plate 33 for engagement with and disengagement from the contacts 110 and 111 of the valve opening circuit, is rigidly attached to the slide 15 of the relay valve 14. When the slide 15 is retained in its lower position by pressure from the train line 1, the switch plate 33 engages the contacts 110 and 111 to complete the valve opening circuit; when the valve slide 15 moves upwardly to cause the air engine 20 to position the brake 27, the switch plate 33 is disengaged from the contacts 110 and 111 to interrupt the valve opening circuit.

It will be noted that a resistance element 74a has been provided in the brake coil energizing circuit. While this resistance element has been shown as inserted in the wire 74, it may, of course, be inserted in the wire 73. The resistance value of the resistance element 74a is normally fixed and is preferably susceptible of adjustment to permit the brake energizing circuits of the respective connected vehicles of a train to be balanced. By so balancing these circuits, uniformity of braking is secured throughout a train.

It will, of course, be understood that, where the air brake train line 1 is connected to similar air brake train lines of adjacent vehicles in the train by means of the hose connections 3, application of any track brake shoe upon any connected vehicle in the train will, through reduction in the pressure of the one train line which includes the air brake train line 1, cause the above-described operation of the valve closing means to shut off power in the traction vehicle. It is contemplated that the principles of this invention may be applied to the tractive ve-

hicle in a train including one or more trailer vehicles, that it may be applied to a plurality of tractive vehicles in such a train or to each vehicle in a train made up solely of traction vehicles. Furthermore, in either of the latter cases it will, of course, be understood that the operation of the valves and the control thereof may be accomplished manually through operation of the hand wheel 71 on the motor shaft or that the above-described mechanism may be made inoperative upon any one or more of the equipped vehicles by manual operation of the switch 83 to isolate the source of power 85 from the primary circuit of the operating mechanism.

In the use of the word "fuel" in the above description and appended claims, steam is comprehended.

It will be understood that the above described structure is merely illustrative of the manner in which the principles of our invention may be utilized and that we desire to comprehend within our invention such modifications as come within the scope of the claims and the invention.

Having thus fully described our invention, what we claim as new and desire to secure by Letters Patent is:

1. In a railway vehicle, electromagnetic track brakes, a fuel supply line, a valve in said supply line, and electrical means responsive to energization of said track brakes to close said valve. 30

2. In a railway vehicle, track brakes, a fuel line, a valve in said fuel line, means for opening and closing said valve comprising a reversible electric motor, and a common circuit for energizing said electric motor and said track brakes. 35

3. In a railway vehicle, track brakes, a fuel line, a valve in said fuel line, means for opening and closing said valve comprising a reversible electric motor operatively connected to said valve, a common circuit for energizing said track brakes 40 and said motor, and means for operating said valve independently of said circuit comprising manual means for operating said motor independently of the energization thereof.

4. In a railway vehicle, a track brake adapted 45 for application by energization of the coil thereof, a fuel line, an electrically operated valve in said fuel line, a common circuit for energizing said brake coil and said electrically operated valve, and a fluid operated circuit switch for said circuit.

5. In a railway vehicle, an air brake train line, a track brake adapted for application by energization of the coil thereof, a fuel line, an electrically operated valve in said fuel line, a common 55 circuit for said brake coil and said electrically operated valve, and a fluid operated circuit switch responsive to the pressure in said air brake train line for opening and closing said common circuit.

6. In a railway vehicle, an air brake train line, 60 a track brake adapted for application by energization, a fuel line, a valve therein, reversible electric means for opening and closing said valve, a common circuit for energizing said brake and said electric means, and switch means responsive 65 to reduction of pressure in said train line for closing said circuit to cause energization of said brake and energization of said electric means to close said valve.

7. In a railway vehicle, an air brake train line, 70 a track brake, means responsive to reduction of pressure in said train line for automatically positioning said brake adjacent a rail, a fuel line, a valve in said fuel line, electric means for opening and closing said valve, a common circuit for ener- 75

- gizing said brake and said electric means, and switch means responsive to the pressure in said train line for opening and closing said common circuit.
5. In a railway vehicle, an air brake train line, a track brake, means responsive to reduction of pressure in said train line for automatically positioning said brake adjacent a rail, a fuel line, a valve in said fuel line, electric motor means for opening and closing said valve, a common circuit for energizing said brake and said electric motor means, and switch means responsive to reduction of pressure in said train line for closing said common circuit to cause energization of said brake and said electric motor means.
9. In a railway vehicle, an air brake train line, a braking means responsive to reduction of pressure in said train line for causing application of said brake, a fuel supply line, a valve in said supply line, and means adapted upon application of said brake automatically to electrically close said valve and adapted upon restoration of pressure to said air train line automatically to electrically re-open said valve.
- 25 10. In a railway vehicle, an air train line, a fuel line, a valve in said fuel line, reversible electric means for opening and closing said valve, a circuit for said electric means, and fluid operated switch means in said circuit responsive to the pressure in said air train line for automatically energizing said electric means to close said valve upon reduction of pressure in said train line a predetermined amount, and to open said valve upon restoration of pressure in said train line above a predetermined value.
11. In a railway vehicle, an air train line, a fuel line, a valve in said fuel line, electric motor means for opening and closing said valve, a circuit for said electric means, and fluid operated switch means in said circuit responsive to the pressure in said air train line, said last-named means being adapted automatically to cause operation of said motor means in one direction to close said valve upon reduction of pressure in said train line below a predetermined value and adapted to cause operation of said motor means in the opposite direction to open said valve upon restoration of pressure in said train line above a predetermined value.
- 40 12. In a railway vehicle, an air train line, a fuel line, a valve in said fuel line, means for opening and closing said valve comprising a reversible electric motor operatively connected thereto, a circuit for said electric motor, and fluid operated switch means in said circuit, said switch means being responsive to the pressure in said air train line for automatically causing rotation of said electric motor in one direction to close said valve upon reduction of pressure in said train line below a predetermined value and to cause operation of said motor in the opposite direction to re-open said valve upon restoration of pressure in said train line above a predetermined value.
- 45 13. In a railway vehicle, an air train line, a fuel line, a valve in said fuel line, a reversible electric motor operatively connected to said valve, an electromagnetic track brake having a coil, a common circuit for energizing said brake coil and said motor, a primary switch in said circuit responsive to pressure in said train line to open and close said circuit, a reversing switch in said circuit operated by said valve, a fluid operated switch in said circuit responsive to the pressure in said air train line, and a fluid operated valve opening circuit interrupting switch in said circuit immediate-
- ly responsive to pressure in said train line to close the valve opening circuit upon restoration of pressure in said train line above a predetermined value.
14. In a railway vehicle, an air train line, a fuel line, a valve in said fuel line, a reversible electric motor operatively connected to said valve, an electromagnetic track brake having a coil, a common circuit for simultaneously energizing said brake coil and said motor, a fluid operated primary switch in said circuit responsive to pressure in said train line for opening and closing said circuit, a reversing switch in said circuit operated by said valve, a fluid operated switch in said circuit responsive to the pressure in said air train line for determining the brush terminal connections of said motor, a fluid operated interrupting switch in the valve opening circuit and responsive to pressure in said train line, and fluid check means between said primary switch and said train line to control the speed of operation thereof.
15. In a railway vehicle, an air train line, a fuel line, a valve in said fuel line, a reversible electric motor operatively connected to said valve, an electromagnetic track brake having a coil, a common circuit for simultaneously energizing said brake coil and said motor, a fluid operated primary switch in said circuit responsive to pressure in said train line for opening and closing said circuit, a reversing switch in said circuit operated by said valve, a fluid operated switch in said circuit responsive to the pressure in said air train line for determining the brush terminal connections of said motor, a fluid operated interrupting switch in the valve opening circuit and responsive to pressure in said train line, and fluid check means between said air train line and said primary switch and fluid operated reversing switch to limit the speed of operation thereof.
16. In a railway vehicle, an air train line, a fuel line, a valve in said fuel line, a reversible electric motor operatively connected to said valve, an electromagnetic track brake having a coil, a common circuit for simultaneously energizing said brake coil and said motor, a fluid operated primary switch in said circuit responsive to pressure in said train line for opening and closing said circuit, a reversing switch in said circuit operated by said valve, a fluid operated switch in said circuit responsive to the pressure in said air train line for determining the brush terminal connections of said motor, a fluid operated interrupting switch in the valve opening circuit and responsive to pressure in said train line, and fluid check means between said air train line and said primary switch and fluid operated reversing switch to limit the speed of operation thereof.
17. In a railway vehicle, an air train line, a fuel line, a normally open valve in said fuel line, and electrical means responsive to reduction of pressure in said air train line below a predetermined value for automatically closing said valve.
18. In a railway vehicle, an air train line, a fuel line, an electrically operated valve in said fuel line, means responsive to reduction of pressure in said air train line below a predetermined value for automatically closing said valve, and means responsive to restoration of pressure in said air train line above a predetermined value for automatically re-opening said valve.
19. In a railway vehicle, an air train line, a brake valve connected to said air train line, a conductor's valve connected to said air train line,

a track trip valve connected to said air train line, a fuel line, a valve in said fuel line, means for electrically opening and closing said valve, said last-named means being responsive to reduction of pressure in said air train line through operation of one of said valves therein to automatically cause said valve operating means to close the valve in said fuel line.

20. In a railway vehicle, an air train line, a 10 brake valve connected to said air train line, a conductor's valve connected to said air train line, a track trip valve connected to said air train line, a fuel line, a valve in said fuel line, means for electrically opening and closing said valve, said last-named means being responsive to reduction of pressure in said air train line through operation of one of said valves therein to automatically cause said valve operating means to close the valve in said fuel line, said valve operating means

including a manual control for manually opening and closing said valve independently of said electrical valve opening and closing means.

21. In means for electrically controlling a fuel valve, a stem in said valve, a reversing switch 5 having a swingable lever electrically connected in a power circuit, a pair of spaced contacts disposed in the path of said lever, each of said contacts being adapted when connected to said lever to energize a valve operating means in an opposite direction, and a projection on said valve stem adapted upon the approach of said valve stem to an extreme position to automatically remove said lever from engagement with one of said contacts and place it in engagement with the other contact, 10 15 whereby to reverse the operating circuit for said valve stem operating means.

THEODORE H. SCHOEPF.

DAVID M. RITCHIE.
